ABSTRACT

An illuminator of a moving target including a line of sight with a laser beam boresighted therein, mechanisms for simultaneous rate and attitude angular displacements of the line of sight in azimuth and elevation and a joystick operable for normal directional control of the respective displacements for rate aided tracking illumination of the target.

SHEET 2 OF 2

FIG. 4

FIG. 3

RATE AIDED TARGET ILLUMINATOR

BACKGROUND OF THE INVENTION

This device is for operation by an observer to designate a moving target for destruction by separate homing means.

SUMMARY OF THE INVENTION

The illuminator includes a rotatable turret and a mirror rotatably disposed therein for respective displacement in azimuth and elevation of a line of sight and a boresighted laser beam, a pair of transmission devices respectively connecting a constant speed motor to the turret and the mirror for transmitting to each simultaneous rate and attitude angular displacements, and a joystick operable for normal directional control of the transmission devices for rate-aided tracking illumination of a target.

BRIEF DESCRIPTION OF THE DRAWINGS

FIG. 1 is an elevation view of the illuminator being operated by an observer;

FIG. 2 is a perspective view of the joystick;

FIG. 3 is a cutaway view of the illuminator body; and

FIG. 4 is a view along line 4-4 of FIG. 3.

DESCRIPTION OF THE PREFERRED EMBODIMENT

An illuminator of a moving target (not shown) includes a body 11 with a turret 13 rotatable in azimuth on a case 15 and with optics including an eyepiece 17, fixed mirrors 19 and 21 with a dove prism 23 therebetween, an object mirror 25 for projecting a line of sight 26 to a target and crosshairs (not shown). A laser source 27 directs a laser beam through mirror 21 for boresighted coincidence with line of sight 26.

Mirror 25 is supported in a frame 29 pivoted in turret 13 about axis 31. A rotatable head 33 of a carriage 35 is secured to frame 29 by tension members 37 and 39 with tension member 39 engaging pulley 41 in turret 13. Flanges 43 of carriage 35 engage pulleys 45 of case 15 for slidable displacement of carriage 35 and lead screw 47 engages carriage 35 for rotation of mirror 25 in turret 13.

Mirror 25 and turret 13 are rotated by identical wormgear and transmission devices 51 from oppositely disposed radial friction disks 53 rotated by constant speed motor 55. Only the transmission device 51 for vertical rotation of mirror 25 is shown.

Rotation of disk 53 is frictionally transmitted to input shaft 57 by spheres 59 retained in carriage 61 of a rate regulator. Output shaft 63 is rotated by an attitude regulator including a carriage 65 secured to output shaft 63 and provided with balls 67 constrained therein for engagement with end 69 of input shaft 57.

The diametrical position of spheres 59 with respect to friction plate 53 to determine the rate of rotation of object mirror 25 is determined by a leadscrew device 71 engaging carriage 61 and rotated by wormgear 73 with pulley 75 thereon.

Wormgear 77 for rotation of output shaft 63 with respect to input shaft 57 is similarly provided with a pulley 79. Pulleys 75 and 79 are respectively belted to pulleys 81 and 83 simultaneously rotatable about axis 87 of a pair of normal axes 87 and 89 of joystick 85. A pair of pulleys are similarly rotatable about axis 89 to control rotation of turret 13.

Dove prism 23 is geared (not shown) to turret 13 for rotation at half speed thereof to retain the target image in erect relation with eyepiece 17 as mirror 25 is rotated in azimuth.

OPERATION

Displacement of joystick 85 in either of the normal directions not only changes the rate of rotation of mirror 25 but also proportionately changes the angular relation of the corresponding input and output shafts and consequently the attitude of mirror 25 for rate-aided procedure.

Tracking a target is an iterative operation in which joystick 85 is operated in either or both of the normal directions to center the crosshairs on a target. As the target moves, the joystick is successively operated with decreasing displacements until the crosshairs track the target (remain centered thereon) without further adjustment of the joystick. The laser is then energized to designate the target by continued illumination thereof for destruction by separate homing means.

Experience has demonstrated that the ratio of attitude to rate change by the transmission devices for normal operation of the illuminator should be two seconds.

A similar ratio of one second can be successfully operated only by highly skilled observers.

We claim:

1. An illuminator for designation of a moving target comprising:

a body including a case, a turret, optics including an object mirror for conducting a line of sight with said turret rotatable on said case, and said mirror rotatably disposed in said turret for respective azimuth and elevation angular displacement of the line of sight, and a laser disposed for generating a beam in boresighted relation with the line of sight; and

a mechanism including a constant speed motor with a pair of rotating disks, a pair of devices corresponding thereto for respective azimuth and elevation transmission to said mirror of simultaneous rotational rates and corresponding angular displacements for rate-aided tracking illumination of the target, and a joystick disposed for operation in normal directions for respective control of said transmission devices.

2. An illuminator as in claim 1 with each of said transmission devices including input and output shafts and rate and attitude regulators respectively disposed between said input shafts and said disks and between said input and output shafts, said azimuth and elevation regulators being respectively disposed for simultaneous control thereof by displacement of said joystick in one of the normal directions.

3. An illuminator as in claim 2 with each of said rate transmission devices including a carriage with a sphere therein disposed for frictional engagement to transmit rotation between one of said disks and the corresponding input shaft, a lead screw device in engagement with said carriage disposed for rotation to vary the radius of contact of said sphere with said disk, and a wormgear device disposed for rotation of said leadscrew device and provided with a pulley; and

with each of said attitude regulators provided with a cage secured to said output shaft and balls secured in said cage for frictional engagement with said input shaft to transmit rotation thereof to said out-

put shaft, and a wormgear device disposed for rotation of said cage and provided with a pulley; and with the pulleys of the respective transmission devices disposed for rotation by said joystick in one of said normal directions for the simultaneous control.

4. An illuminator as in claim 3 with a frame secured to said mirror and pivoted in said turret for the elevation displacement; a carriage provided with a head and disposed for slidable displacement in said case and a leadscrew device secured to said carriage and provided

with a wormgear in engagement with said output shaft for the slidable displacement, said head being secured to said frame for rotation of said object mirror and rotatably disposed in said carriage to permit rotation of said turret.

5. An illuminator as in claim 4 with said transmission devices disposed to provide a ratio of displacements to rotational rates equal to two seconds for normal operation of the illuminator.
